UNITED STATES PATENT OFFICE.

JOHN WALTER, OF NASHVILLE, TENNESSEE, ASSIGNOR TO THE NATIONAL SHEET METAL ROOFING COMPANY, OF SAME PLACE.

METAL ROOFING.

SPECIFICATION forming part of Letters Patent No. 309,175, dated December 9, 1884.

Application filed April 14, 1884. (No model.)

To all whom it may concern:

Be it known that I, JOHN WALTER, of Nashville, in the county of Davidson and State of Tennessee, have invented a certain new and useful Improvement in Metal Roofing, of which the following is a full, clear, and exact description, reference being had to the accompanying drawings.

This invention relates to metal plates for roofing buildings, and particularly to the kind of plates shown and described in United States Patent No. 256,083, issued to me April 4, 1882; and the improvement consists in the manner of arranging such plates when laying them upon a building.

In the drawings, Figure 1 is a top view of the plates as they appear when secured to a building, and Fig. 2 is a section of the same on plane *xx*.

In these views A represents one of the plates; B and C, two parallel corrugations near one of its side edges; D, a gutter between such corrugations; E, a flange by which the plate is nailed to the building; F, a broad corrugation on the opposite side of the plate, the edge of which is bent inwardly, so as to engage with the corrugation B of an adjacent plate to form a lock-seam, G, between the plates, the corrugation itself covering the gutter D; H, a transverse corrugation near the upper end of the plate, that prevents capillary action between the overlapping ends of the plates of adjacent layers; I, a centrally-located corrugation of a shape like an inverted Y, that turns the water from the overlapping end of the plate to the sides thereof, to prevent flooding the joint between adjacent layers; J, an arrow-head corrugation located in the bifurcation of the Y-corrugation, which also serves to guide the water from the lower or overlapping end to the sides, all of which is more fully referred to in said patent. The said patent also described the plates which form any upper layer as so laid in relation to the plates of any adjacent lower layer that the lock-seams uniting the plates coincide or are in the same right lines from the lower to the upper layer; but in the present case the plates are combined and arranged in a manner to avail of the advantages of the common break-joint method. Thus the seams G, that

unite the plates of any upper layer, coincide with and form practically extensions of the central corrugations I of the plates of the next lower layer. So, also, the central corrugations J of the plates of any upper layer overlap the seam G between the plates of the next lower layer. By this arrangement of the plates there is but one thickness of metal under or over the lapping parts of the seams between the plates, while heretofore the seams themselves overlapped, and hence the plates can be laid closer to the structure they are to protect, thereby being less subject to the action of wind, accomplishing their purpose more certainly and presenting a better appearance. The discharge from the gutters in the seams and the flow of water at the sides of the plates are divided and diverted by each layer of plates, and therefore the water cannot, as heretofore, collect in currents of such volume as to flood the seams between the plates. The central Y-corrugations, abutting as they do against the ends of the seams, tend to protect their open ends and contained gutters, and the stems of the arrow-head corrugations, fitting as they do closely around the seams at their upper ends, more surely prevent water from getting in such seams than when the seams lie upon one another.

What is claimed as new is—

1. The combination of layers of sheet-metal plates A in such manner that the seams G between the plates of an upper layer shall coincide with and form an extension of a central corrugation, I, formed in the plates of the next lower layer, substantially as set forth and shown.

2. The combination of layers of sheet-metal plates A in such manner that the seams G between the plates of an upper layer shall coincide with and form extensions of central corrugations I, formed on the plates of the next lower layer, and the central corrugations, J, of said upper plates shall overlap the seams G of said lower plates, substantially as described and shown.

JOHN WALTER.
